Primary Examiner — Shannon W Morgan

Assistant Examiner — Alonso Sanchez Giddens

(57) **CLAIM**

The ornamental design for a knee pad, as shown and described.

DESCRIPTION

FIG. 1 is a front, top perspective view of a knee pad, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is another perspective view thereof, shown in an alternative position; and,

FIG. 10 is an enlarged view of detail "10" identified in FIG. 1.

The dashed lines in the figures illustrate portions of the knee pad that form no part of the claimed design. The dash dot dash lines in FIGS. 1 and 10 are for the purpose of illustrating the enlarged view indicators and form no part of the claimed design.

1 Claim, 10 Drawing Sheets
